UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

PUMP.

1,357,671.

Specification of Letters Patent. Patented Nov. 2, 1920.

Application filed October 5, 1917. Serial No. 194,846.

To all whom it may concern:

Be it known that I, BURTON S. AIKMAN, a citizen of the United States, residing at Milwaukee, in the county of Milwaukee and 5 State of Wisconsin, have invented a certain new and useful Improvement in Pumps, of which the following is a full, clear, concise, and exact description, reference being had to the accompanying drawings, forming a part 10 of this specification.

My invention relates to pumps and particularly to that type of pump used in a pumping system, which may be employed as an isolated plant for furnishing water to a 15 residence or an industrial establishment from a nearby source, such as a well.

It is the purpose of my invention to provide an improved pump for use in a system which supplies water "fresh from the well", 20 that is, without the intervention of a storage or reserve tank and which will be under "faucet control" by which I mean that the flow of water is controlled by opening and closing the faucets which form the supply 25 outlet of the system.

The pump operates so long as it is supplied with compressed air and has a free 30 outlet for the water. If the outlet is completely shut off, as when all the faucets are closed, the pump ceases to operate. As soon as an outlet is provided, as by opening a faucet, the pump again operates. As the 35 running of the pump is dependent upon the provision of an outlet, as by opening the faucets, this type of system is designated a "faucet control" system.

The object of the present invention is to provide a pump of this class which is efficient, simple, rugged and inexpensive to 40 manufacture or to operate. Many of the pumps of this general type now found on the market are inefficient in the use of compressed air, or motive fluid. This is generally the fault of poor design and construction and particularly it is due to the fact that in many of the prior art devices a separate air motor fed independently with compressed air is employed to operate the 45 valves.

50 I employ the air which works the valves in the body of the pump to perform work, thus a maximum efficiency of the air is secured.

55 Another disadvantageous feature of the prior art devices is the fact that they use the

air non-expansively. This is because the valves are purely level controlled.

According to the present invention, the air is used expansively, that is, the air is permitted to work so long as it has sufficient 60 pressure to do so before it is exhausted. This is secured by providing pressure control in addition to the usual level control. A further advantage of the present invention is the ability to dispense with a maintaining valve and employ a simple reduction valve.

A further advantage is the ability to make up the device in small size of few parts and of rugged construction. It is impossible for 70 the valve mechanism to become so set that air can blow through the device without doing work. Numerous other advantages will be apparent from the following specification.

75 One embodiment of my invention is illustrated in the accompanying drawings, in which—

Figure 1 is a more or less diagrammatic view illustrating the system as a whole;

Fig. 2 is a vertical axial sectional view of the pump; and

Fig. 3 is a vertical axial sectional view taken on the plane of the line 3, 3 of Fig. 2 and looking in the direction indicated by the 85 arrow.

As shown diagrammatically in Fig. 1, the pump 4 is disposed in the well, the curbing of which is shown at 5, below the level 6 of the water so that the pump automatically fills at the proper time, as will be described later. The pump structure has leading therefrom three pipes, an air pressure pipe 7, an exhaust pipe 8, and a water discharge pipe 9. The water discharge pipe 9 95 is connected with the air spring 10 and with various branch pipes 11, 11, each of which is provided with a faucet 12. The air pressure pipe 7 is connected through the reducing valve 13, and the pipe 14 and 15, with a compressed air tank 16, in which air is stored under pressure as by means of a suitable compressor 17 driven by the motor 18. It will be apparent to those skilled in the art that the compressor may be operated by 105 any other motor such as a gas engine, steam engine, or the like, and if desired, means may be provided for automatically starting and stopping the motor when the pressure in the tank drops to a prescribed minimum 110

and rises to a prescribed maximum, respectively.

It can now be seen that this system represents an isolated plant for installation in a 5 residence or the like. The water discharge pipe leads from the well conveniently nearby to the distributing pipe in the building and the compressor, motor, compressor tank and chamber may be suitably housed in any 10 convenient manner.

The pump 4 is shown in detail in Figs. 2 and 3. The pump comprises a cylindrical barrel 22, preferably in the form of a piece of seamless brass tubing. The upper end 15 of the barrel is closed off by a head casting 23 and the lower end of the barrel is closed off by the foot casting 24. The head casting 23 and the foot casting 24 are held together upon the ends of the barrel 22 by means of 20 the tie pipes 25 and 26 which serve also as discharge pipes. At their upper ends these pipes are screwed into suitable openings provided in the head casting 23 and at their lower ends these pipes are screwed into suit- 25 able openings in the upper part of the valve cage 27. The valve cage 27 is connected to the foot member 24 by means of the central bolt 28. The valve cage 27 incloses the check valve 29 which controls a port 30 communicat- 30 ing with the lower part of the pump cylinder 22 by way of the passageways 31. The foot member 24 is provided with inlet ports 32 which are controlled by the check valve 33. A conical screen 34 covers the 35 bottom of the foot member 24 and prevents the entry of foreign matter to the pump cylinder. Suitable packing, as shown at 35 and 36, serves to make a tight joint between the ends of the barrel and the head and foot 40 castings, respectively.

The air inlet pipe 7, air exhaust pipe 8, and water discharge pipe 9 are threaded, respectively, into the air inlet 37, exhaust air outlet 38 and water discharge outlet 39 of 45 the head casting 23 of the pump. The water outlet 39 is in communication with the pipes 25 and 26 by means of the passageway 40.

The air inlet 37 communicates with the 50 interior of the pump cylinder 22 by means of the passageways 41 and 42, diaphragm chamber or cylinder 43, and passageways 44, 45, 46 and 47. The passageway 41—42 is of smaller size than the passageway 55 44—45—46—47 so that there is normally a reduction of pressure due to the restricted flow, in the cylinder 43. The passageway 47 is formed through a removable nipple which forms a valve seat. This valve port 60 47 is controlled by a valve member 48, mounted on the arm 49 of a bell-crank lever 50. The bell-crank lever 50 rocks upon a bolt 51, bearing in the arms 52 which project from the head casting 23. The arm 53 65 of the bell-crank lever has pivotally con-

nected thereto a water weight 54 by means of the link 55. The opposite arm 56 of the bell-crank lever 50 is provided with projecting pins 57, 57 which are connected at their ends to the springs 58, 58, these springs being connected at their upper ends to the head casting 23. The water weight 54 comprises a hollow cylindrical body consisting of a shell of metal 59, preferably a tube of brass or bronze, or the like, and having its 75 lower end closed by a head 60, this head being provided with a guiding pin 61, which is guided in a suitable bracket 62 projecting from the valve cage 27. The head 60 has projecting therefrom an arm 63 to which is 80 secured a spring 64, this spring being connected at its upper end to the bracket 65, which is clamped about the pipes 25 and 26. The spring 64 serves to counterbalance a part of the weight of the float or water 85 weight 54. I have found that a float may be employed where for certain reasons it is desirable. In that case the springs 58 are eliminated.

Referring now to the mechanism for controlling the exhaust, it will be seen that a portion of the diaphragm chamber or cylinder 43 is formed in the head casting 23 and the other portion is formed by providing a suitable recessed member 67, which is 90 secured to the head casting 23 by means of suitable screws, the diaphragm 68 being clamped and held in place between the member 67 and the head casting. The head casting 23 has provided, in a suitable pocket, a 95 sleeve member 69, through which a stem 70 slides freely. The stem 70 is reduced in diameter at each end, one end being threaded and clamped to the diaphragm 68 by means of the lock nut 71 and the other end being 100 firmly secured to the valve 72 controlling the port 73 communicating with the exhaust outlet 38. The valve 72 seats with the pressure in the pumping chamber and hence 105 always tends to remain tight while under pressure. A spring 74 is placed between the head casting and the diaphragm 68 to hold normally the valve 72 tight against its seat, thus closing off the exhaust port 73. The valve 72 closes off the port by means of a 110 double seat so that no packing for the sleeve 69 is necessary.

When the pump is submerged in the water and the exhaust valve is open the water will pass through the openings in the screen 120 34 up through the port 32, past the check valve 33, and substantially fill the cylinder 22. As the level of the water in the pump tends to rise, the water weight 54 also tends to rise due to the springs 64 and the support afforded by the water until the upward thrust is sufficient to overcome the pull of the springs 58—58. The bell-crank lever 50 then turns quickly about its pivot and causes the passageway 47 to be uncovered 125 130

with a sharp snap. When the water is driven out of the barrel obviously the water weight will move to its lowest position, thereby causing the bell-crank lever 50 to 5 turn about its pivot 51, in a clockwise direction in Fig. 3, thus causing the valve 48 to close off the passageway 47. The springs 58, 58 cause the valve 48 to open and close positively and quickly with a snap action. 10 The maximum resistance offered by these springs occurs in their outermost position. Hence as soon as the water weight 54 overcomes the initial tension in either direction the valve opens and closes at once. 15 I find it desirable in the operation of the pump to keep the port 47 closed by the valve 48 until the pump is substantially full of water and to accomplish this result I provide the flow controlled brake 75. This 20 brake consists of a bell-crank lever pivotally secured to the upper part of the valve cage 27, one arm of which bears against the guiding rod 61 secured to the water weight 54 and the other arm of which is attached to a circular plate 76. The plate 76 is disposed horizontally in the pump cylinder and covers considerable area. When the water in the pump rises the plate is pushed upwardly by the incoming current of water, 25 causing one arm of the bell-crank lever 75 to press against the rod 61 and hold the water weight down. When the pump is substantially full of water the flow into the pump abates and the brake is released, which permits the water weight to rise and open the 30 valve 48.

A passageway 77 is provided from the interior of the pump to the chamber on the right-hand side of the diaphragm 68 so that when air is admitted to the interior of the pump the pressures on both sides of the diaphragm 68 tend to equalize. The passageway 41 is restricted in area, while the passageways 44, 45, 46 and 47 are of considerably larger 45 area. This permits the air to pass freely out of the diaphragm chamber 43 to the interior of the pump and around to the right hand side of the diaphragm 68, thus preventing the exhaust valve 69 from opening 50 until the proper time, as no pressure builds up in the chamber on the front side of the diaphragm.

Assuming the pump to be connected to a system as shown in Fig. 1 with the parts 55 in the position shown in Figs. 2 and 3, the operation of the pump and the system is as follows:

When a faucet is opened, water will flow 60 out of the air spring 10, thus lowering the pressure of the water therein and permitting the pump to operate. The air passes through the restricted passageways 41 and 42 into the diaphragm chamber 43 and through the passageways 44, 45, 46 and 47 65 to the interior of the pump cylinder. The

pump being full of water, the water is forced down in the pump cylinder through the passageways 31, 31, port 30, past the check valve 29, up through the pipes 25 and 26, through the passageway 40, pipe 9, and to 70 the air spring 10 and consumption mains 11, 11, from which it may be drawn through a faucet for use. As the water passes out of the pump cylinder, the water weight 54 tends to drop. When the downward pull 75 becomes great enough to overcome the springs 58, 58 the water weight causes the valve 48 to close, thus cutting off the supply of air to the interior of the pump. The pressure then builds up on the left hand 80 side, *i. e.*, the front of the diaphragm 68 until it is sufficiently higher than the pressure of the air in the body of the pump which latter pressure is exerted on the back of the diaphragm 68 to overcome the tension of the spring 74, thus forcing the valve 72 away from its seat against the pressure of the motive fluid tending to hold it to its seat and permitting the air to exhaust. When the pump cylinder has been exhausted 90 the water will again rise in the pump until it is substantially full of water. Then the water weight 54 will be released and rises opening the valve 48 and air again is admitted to the pump. It will be seen that 95 water may pass either to the consumption mains 11, 11 or into the air spring 10. The air cushion in the chamber 10 fills in the gap between the strokes of the pump so that the flow of water at the faucets 12-12 100 is substantially constant and no cessation of pressure is noticeable. When all of the faucets 12-12 are closed and no water is being consumed the pressure backs up and stalls the pump. It can now be seen that 105 no separate air motor for operating the valves is necessary as the air which operates the valves in the above device is discharged into the body of the pump to pump water.

It is impossible for a blowover to occur 110 as the pressure must be built up in the front chamber 43 higher than the pressure in the body of the pump before the exhaust valve 72 can be opened as the exhaust valve 72 is held to seat by the pressure of the motive 115 fluid within the pumping chamber. This pressure can build up only after the air admission valve 48 is closed.

The efficiency of the pump is marked 120 because of the fact that expansion of the air is permitted after the control valve 48 is closed. This is secured by requiring a difference of pressure on the two sides of the diaphragm 68 before the exhaust valve can be opened.

No maintaining valve is necessary because 125 of the difference in pressure required on opposite sides of the diaphragm 68. The reducing valve keeps excessive pressure from forming when the faucets are closed 130

and the restricted orifice 41 prevents overworking of the pump when the faucets are all opened wide.

If one of the faucets is just open enough 5 to permit of a dripping at the same the valve action cannot become centered and cause a blowover because of the requirement to build up pressure in the front chamber 43 after the valve 48 is closed and a 10 drop in pressure outside before the exhaust valve can open.

I claim:

1. In combination, a main pump barrel having water inlet and outlet valves, an 15 exhaust valve, a diaphragm connected to the exhaust valve, one side of the diaphragm being subject to the pressure in the interior of the barrel, a chamber on the other side of the diaphragm having a restricted com- 20 pressed air inlet port and a relatively free outlet port from the chamber into the pump barrel, and a valve governed by the level of the water for controlling the outlet port.

25 2. In combination, a main pump barrel having water inlet and outlet valves, an exhaust valve, a diaphragm connected to the exhaust valve, a chamber on one side communicating with the interior of the barrel, 30 a chamber on the other side having a restricted compressed air inlet port and a relatively free outlet port from the chamber into the pump barrel, a valve, and a level controlled device for governing the valve.

35 3. In combination, a pump barrel, an exhaust valve, a movable pressure controlled member connected to said valve, a chamber communicating with the interior of the barrel on one side of the member, a cham- 40 ber communicating with a source of motive fluid on the other side of the member and a level controlled valve governing said member.

4. In combination, a pump barrel, an ex- 45 haust valve for the barrel, a pressure controlled device subject to the pressure within the barrel and a level controlled device subject to the level of the liquid in the barrel, said exhaust valve being jointly controlled by said devices.

5. In combination, a pump barrel, an ex- 55 haust valve, a pressure element subject to the pressure in the barrel for controlling the exhaust valve, and an inlet valve govern- 60 ing said pressure element.

6. In combination, a pump barrel, an ex- haust valve, a pressure element subject to the pressure in the barrel for controlling the exhaust valve, an inlet valve govern- 65 ing said pressure element, and a level controlled device governing said inlet valve.

7. In combination, a pump barrel, an ex- haust valve, and a pressure element subject to the difference in pressure between the 65 incoming motive fluid and the pressure

within the barrel for operating said exhaust valve.

8. In combination, a pump barrel, an exhaust valve, a pressure element subject to the difference in pressure between the incoming motive fluid and the pressure within the barrel for operating said exhaust valve, and an inlet valve controlling the application of the pressure of the motive fluid to said element. 75

9. In combination, a pump barrel, an exhaust valve, a pressure element subject to the difference in pressure between the incoming motive fluid and the pressure within the barrel for operating said exhaust valve, an inlet valve controlling the application of the pressure of the motive fluid to said element, and a level controlled device governing said valve. 80

10. In combination, a closed pump cylinder, admission and exhaust ports for said cylinder, water inlets and discharge passageways for said cylinder, valves controlling said admission and exhaust ports, means controlled by the level of the water in said cylinder for operating the valve to said admission port, and means controlling the valve to said exhaust port operative only when the valve to said admission port is closed. 90

11. In combination, a closed pump cylinder, admission and exhaust ports for said cylinder, water inlets and discharge passageways for said cylinder, valves controlling said admission and exhaust ports, a water weight within said cylinder for operating the valve to said admission port, and means controlling the valve to said exhaust port, operative only when the valve to said admission port is closed. 95

12. In combination, a closed pump cylinder, admission and exhaust ports for said cylinder, water inlet and discharge passageways for said cylinder, valves controlling said admission and exhaust ports, a level controlled device within said cylinder for operating the valve to said admission port, means controlling the valve to said exhaust port, and means to hold the valve controlling said admission port closed until the cylinder is substantially full of water. 110

13. In combination, a closed pump cylinder, admission and exhaust ports for said cylinder, water inlet and discharge passageways for said cylinder, valves controlling said admission and exhaust ports, a level controlled device within said cylinder for operating the valve to said admission port, means controlling the valve to said exhaust port, and a brake associated with said level controlled device to hold the same down until the pump is substantially full of water. 120

14. In combination, a closed pump cylinder, admission and exhaust ports for said cylinder, water inlet and discharge passageways for said cylinder, valves controlling 130

5 said admission and exhaust ports, means controlling the valve to said exhaust port, means controlling the valve to said admission port, a level controlled device in said cylinder, and means controlled by said level controlled device for imparting a snap action to said admission valve controlling means.

10 15. In a pump, a cylinder, a cylinder head member having a chamber for a diaphragm, an air admission port communicating with said diaphragm chamber, a passageway leading from said chamber to the interior of said cylinder, a valve controlling said passageway, an exhaust port communicating with the interior of said cylinder, a valve controlling said exhaust port and operated by said diaphragm, and means controlled by the level of the water in the cylinder for operating the valve controlling said admission passageway.

15 20 25 30 35 40 45 50 55 60 65 16. In a pump, a cylinder, a cylinder head member having a chamber for a diaphragm, an admission port, a restricted passageway leading from said port to said diaphragm chamber, a relatively free passageway leading from said chamber to the interior of said pump cylinder, a valve controlling said relatively free passageway, an exhaust port communicating with the interior of said cylinder, a valve controlling said exhaust port and operated by said diaphragm, and means controlled by the level of the water in the cylinder for operating the valve controlling said relatively free passageway.

17. In a pump, a cylinder, a cylinder head member having a chamber for a diaphragm, an air admission port communicating with one side of said diaphragm chamber, a passageway leading from said chamber to the interior of said cylinder, a valve controlling said passageway, a passageway leading from the interior of said cylinder to the other side of said diaphragm chamber, an exhaust port communicating with the interior of said cylinder, a valve controlling said exhaust port and operated by said diaphragm, and means controlled by the level of the water in the cylinder for operating the valve controlling said admission passageway.

18. In a pump, a pumping cylinder having inlet and discharge valves for liquid, admission and exhaust valves for motive fluid, a motor for operating one of the valves for motive fluid, a level controlled device governing said motor, and means for discharging the exhaust of the motor into the cylinder during the admission period of the cylinder.

19. In a pump, a cylinder having inlet and discharge valves for liquid, admission and exhaust valves for motive fluid, a motor for operating the exhaust valve, a level controlled device governing said motor and means for discharging the exhaust of the

motor into the pump cylinder and opening the admission valve of the cylinder, said means being responsive to high level conditions in the cylinder.

20. In combination, a pump cylinder having inlet and discharge valves for liquid, admission and exhaust valves for motive fluid, a motor for operating the exhaust valve and level controlled means responsive to low level conditions in the cylinder governing the effective application of pressure to the motor to open the exhaust valve, said motor having a connection with the pump cylinder for discharging the exhaust from the motor cylinder into the pump cylinder. 70 75 80

21. In a pump, a cylinder having inlet and discharge valves for liquid, admission and exhaust valves for motive fluid, said exhaust valve having a yielding face and being adapted to be held to its seat by the pressure of motive fluid within the cylinder, a motor having a flexible diaphragm for operating the exhaust valve in one direction, spring means for making the return stroke of the motor, and level controlled means responsive to low level conditions in the cylinder governing the application of pressure to the motor to open the exhaust valve. 85 90

22. In a pump, a pumping cylinder, inlet and discharge means for liquid, admission and exhaust passageways for motive fluid, an exhaust valve, a pressure operated motor, said motor comprising a pressure chamber and a movable piston, and level controlled means governing the accumulation of pressure in said pressure chamber, said motor controlling the operation of said exhaust valve, said motor discharging its exhaust into the pumping cylinder. 95 100

23. In a pump, a pumping cylinder, inlet and discharge means for liquid, admission and exhaust passageways for motive fluid, an exhaust valve, a pressure operated motor adapted to communicate with the admission passageway, said motor comprising a pressure chamber and a movable piston and means controlled by the low level of liquid in the pumping cylinder for controlling the application of pressure to the piston, said motor controlling the operation of the exhaust valve, the exhaust of said motor being discharged into the pumping cylinder when the cylinder is filled with water. 105 110 115

24. In combination a pump barrel, comprising a cylinder, an admission passageway, an admission port, an exhaust port, a valve for the exhaust port, means tending to close the exhaust port, a valve for the admission port, a level controlled device governing said admission valve, and a motor having a motor chamber connecting with the admission passageway and the admission port, said motor controlling said exhaust port. 120 125

25. In combination, a pumping chamber, 130

inlet and discharge valves for liquid, an admission passageway for motive fluid, an admission port for admitting motive fluid to the pumping chamber from the passageway, 5 a motor cylinder communicating with the admission passageway, a piston for the cylinder, an exhaust valve controlled by the piston, and a float responsive to the low level of liquid for controlling the effective application of pressure to the piston, said motor cylinder having a restricted opening for the admission of motive fluid.

26. In combination, a source of motive fluid, a pump barrel subject to high level 15 and to low level conditions therein, an exhaust port, an exhaust valve therefor, an inlet port, an inlet valve therefor, a float controlled by one level condition for operating one of said valves for each pump stroke, 20 and a pressure motor having a cylinder communicating with the source of motive fluid through a restricted connection and having a piston operated by the pressure of the motive fluid within the cylinder upon the other extreme level condition for controlling the other of said valves for each pump stroke.

27. In combination, a source of motive fluid, a pump cylinder having air inlet and exhaust valves, a motor having a diaphragm, said motor having a restricted 30 communication with the source of motive fluid, one of said valves being operated by said diaphragm for each stroke of the motor, a spring for the diaphragm for holding 35 the diaphragm in one extreme position, a float controlling the other valve, said float and other valve controlling the application of pressure to said diaphragm to overcome the pressure of the spring to shift the first 40 valve for each stroke of the pump.

28. In combination, a pump cylinder having water inlet and discharge ports, admission and exhaust ports, admission and exhaust valves therefor, level controlled 45 means for controlling said valves for each stroke of the pump, and flow controlled means subject to the flow of water into the cylinder for controlling the movement of said level controlled means.

50 29. In combination, a pump cylinder having a water inlet port, a water discharge port, an exhaust air port and an air inlet port, a passageway leading from the air inlet to the interior of the pump, said passageway comprising a pressure cylinder, an inlet valve controlling said passageway, a float valve controlled by high level for causing the pressure to build up in said pressure cylinder, a piston for the pressure cylinder, 55 and a valve controlled by the movement of said piston, said valve controlling one of said air ports.

60 30. In a pump, a cylinder having inlet and discharge passages for liquid, admission and exhaust passages for motive fluid, a

motor for operating the exhaust valve, and a low level controlled valve governing said motor, said motor being adapted to discharge the exhaust therefrom back into the cylinder.

70

31. In combination, a pump cylinder, a motor cylinder, a motor piston for said latter cylinder, an exhaust valve controlled by said piston, a spring for holding the piston at one end of its stroke and for holding the 75 exhaust valve closed, and a float controlled valve controlled by the low level in the cylinder and a motive fluid port controlled by the float valve for controlling the pressure within the cylinder to open the exhaust 80 valve.

32. In combination, a cylinder, a head member for closing the top of the cylinder, a foot member for closing the bottom of the cylinder, a valve box in the cylinder, said 85 box having a valved port for permitting the water to be driven from the pump cylinder into the box, a water discharge passageway in the head member, a pipe connecting the passageway in the head member 90 with the box, and a threaded pin connecting the valve box and foot member, said pipe, box and pin serving as a mechanical connection between the head member and the foot member.

95

33. In combination, a cylinder, a head for the cylinder, a foot member for the cylinder, connecting means for the head and foot member, said connecting means lying within the cylinder, said foot member comprising a central boss having an annular opening, comprising a water inlet port, an annular valve for said port and a central guide for said valve, said central guide being connected to said foot member.

100

34. In combination, a cylinder, a head member, a foot member, said foot member comprising a central boss, means comprising a rod for connecting the head member and the foot member, said rod passing through 110 said central boss, said foot member having an annular inlet port about said central boss, and an annular valve for controlling said port.

35. In combination, a pump chamber comprising a cylinder having a head member and a foot member, said head member having a valve and motor member mounted thereon and disposed within the cylinder, said member having air inlet and exhaust 115 valves, and a valve operating motor having a diaphragm, one of said valves being operated by said diaphragm for each stroke of the pump, a spring for the diaphragm for holding the diaphragm in one extreme 120 position, the other valve being level controlled, said other valve controlling the application of pressure to said diaphragm to overcome the pressure of the spring to shift the first valve for each stroke of the pump. 130

36. In combination, a pumping chamber comprising a cylinder, a head member and a foot member, a valve and motor structure mounted on the lower side of the head and disposed within the cylinder, a head structure comprising an inlet and an exhaust valve and a motor for operating one of said valves, and a float for operating the other of said valves, said other valve governing the application of pressure to said motor for operating said one valve.

37. In combination, a pumping chamber, a main exhaust valve, a pressure motor, a restricted passageway providing constant communication between the source of motive fluid and the pressure motor, an exhaust port for the pressure motor opening into the pumping chamber, said exhaust port being of larger capacity than the restricted passageway, and a level controlled valve governing said exhaust port.

38. In combination, a pumping chamber, a main exhaust valve, a pressure motor, a restricted passageway providing constant communication between the source of motive fluid and the pressure motor, an exhaust port for the pressure motor opening into the pumping chamber, said exhaust port being of larger capacity than the restricted passageway, means to seat the main exhaust valve with the pressure of the motive fluid in the pumping chamber, and a level controlled valve governing said exhaust port.

39. In combination, a pump cylinder having air inlet and exhaust valves, a motor having a diaphragm, one of said valves being operated by said diaphragm for each stroke of the motor, a spring for the diaphragm for holding the diaphragm in one extreme position, said diaphragm being exposed on the side of the spring at all times to the pressure prevailing within the cylinder, a float controlling the other valve, the float and other valve controlling the application of pressure to said diaphragm to overcome the pressure of the spring, to shift the first valve for each stroke of the pump.

40. In combination, a source of motive fluid a pumping chamber, an exhaust port for the pumping chamber, an exhaust valve for said port, said exhaust valve being held to seat by the pressure within the pumping chamber, a pressure motor having a movable member subjected on one side to the pressure of motive fluid within the pump chamber and having a chamber on the other side provided with a restricted but constantly open communication to the source of motive fluid and a float controlled valve governing the exhaust of pressure from said latter chamber.

41. In a pump, a cylinder having a head member, liquid check valves for the cylinder,

an air admission valve, an air exhaust valve, ports for said valves formed in said head, 65 said exhaust valve having a yielding face adapted to be held against its seat by internal pressure, said admission valve being of relatively smaller size than the exhaust valve and being adapted to be held to seat 70 against the pressure of the motive fluid, a pressure motor comprising a flexible diaphragm for moving the exhaust valve away from seat against the internal pressure of the cylinder when the water has been driven 75 from the pump cylinder and level responsive means adapted at low level to cause said admission valve to close.

42. In a pump, a cylinder having a head member, liquid check valves for the cylinder, 80 separate air admission and air exhaust valves for the cylinder, ports for said valves formed in said head, said exhaust valve having a yielding face adapted to be held against its seat by internal pressure, said admission valve being of relatively smaller size than the exhaust valve, a pressure motor mounted on said head and comprising a flexible diaphragm for moving the exhaust valve 85 away from seat against the internal 90 pressure of the cylinder when the water has been driven from the pump cylinder and level responsive means controlling said motor at low level to open the exhaust valve, said exhaust valve being adapted to be held 95 open and said admission valve adapted to be held closed until water has substantially filled the pump chamber.

43. In a pump, a cylinder, liquid check valves for the cylinder, a pressure motor 100 having a chamber and a movable member adapted to be operated by motive fluid, a restricted passageway connecting said chamber with a source of motive fluid, a main exhaust valve adapted to seat with internal 105 pressure and adapted to be moved off seat against said internal pressure by the movable motor member, a control valve for exhaust of the motor and means responsive to level in the pumping chamber for operating said control valve.

44. In a pump, a cylinder having liquid check valves, a pressure motor having a chamber and a movable member adapted to be operated by motive fluid, a constantly 115 open restricted passageway connecting said chamber with a source of motive fluid, a main exhaust valve adapted to seat with internal pressure and adapted to be moved off seat against said internal pressure by the 120 movable motor member, an exhaust valve for the motor and a level responsive device controlling said motor exhaust valve.

In witness whereof I hereunto subscribe my name this 1st day of October A. D. 1917. 125
BURTON S. AIKMAN.
